TEACHING MACHINE TOY HAVING PHONOGRAPH MEANS

John W. Ryan, Los Angeles, and Eugene J. Echterling,
Manhattan Beach, Calif., assignors to Mattel, Inc., a
corporation of California

Filed Jan. 25, 1967, Ser. No. 5,557

Term of patent 14 years

(Cl. D25—1)

FIGURE 1 is a side elevational view of a teaching machine toy having phonograph means showing our new design;

FIGURE 2 is a top plan view thereof;

FIGURE 3 is an end elevational view taken from the left of FIGURE 1;

FIGURE 4 is an end elevational view taken from the right of FIGURE 1; and

FIGURE 5 is a side elevational view of the side opposite FIGURE 1.

We claim:

The ornamental design for a teaching machine toy having phonograph means, as shown.
